FOUNTAIN OR THE LIKE

Carl Price, 17218 Escalon Drive, Encino, Calif. 91316

Filed Oct. 15, 1969, Ser. No. 19,584

Term of patent 14 years

Int. Cl. D23—01

U.S. Cl. D23—13

FIG. 1 is a front perspective view of a fountain embodying my new design;

FIG. 2 is a rear elevational view thereof;

FIG. 3 is a top plan view thereof; and

FIG. 4 is a partial front elevational view thereof with broken lines depicting the fountain in operation for illustrative purposes.

I claim:

The ornamental design for a fountain or the like, as shown and described.
